HEAT EXCHANGERS

Ferdinand Lustwerk, Lincoln, Harold S. Mickley, Belmont, and Ernest P. Neumann, Lincoln, Mass., assignors, by mesne assignments, to Rheem Manufacturing Company, a corporation of California.

Application July 13, 1954; Serial No. 443,028

3 Claims. (Cl. 62—156)

This invention relates to heat exchangers, more particularly to a refrigerant condenser of the type shown and described in co-pending application, Serial No. 427,049, filed May 3, 1954, and to improvements in a refrigeration system embodying said condenser.

In a compression type refrigeration system, a suitable refrigerant capable of evaporation from a liquid to a gaseous phase at low temperature is circulated in a closed circuit. When it evaporates at low pressure in the evaporator, it absorbs heat, thus producing the desired refrigeration. The evaporated gas is compressed in a compressor and then cooled in a condenser to revert it to its liquid phase at a substantially higher temperature than its temperature of evaporation at low pressure, after which it returns to the evaporator.

Our invention provides an improved condenser and we have discovered that the condenser, when used in a compression type refrigeration circuit, including means to evaporate and then to compress a refrigerant, increases efficiency as much as double. This increased efficiency results in part by greatly reducing the power per ton of refrigeration required to compress the refrigerant, reducing power required to operate the fans, reducing the amount of coolant water used and reducing the power required to circulate the coolant water. Such increased efficiency is reflected in greatly reduced capital costs for refrigeration and air conditioning units and the like.

The standard commercial refrigerating unit, such as is used in domestic refrigerators and air conditioning systems, requires a motor rated at about one horsepower to produce a ton of refrigeration per day, a ton of refrigeration being equivalent to that produced by the melting of one ton of ice. We can now use a motor rated at one horsepower for the compressor to produce refrigeration which is equivalent to that which was heretofore produced by a motor rated at two horsepower.

In a refrigeration system this power requirement is proportionate to the difference between the temperature of evaporation of the refrigerant from liquid to gas and the temperature of condensation of the compressed gas back to liquid. Our invention increases efficiency by reducing the temperature of condensation from temperatures of the order of 125° F. and upward in the usual system to temperatures of the order of 100° F. or less.

Water is the most readily available coolant for use with a condenser for cooling refrigerant. When used in substantial quantities it ordinarily has good cooling properties, but such quantitative use may amount to a substantial item of the cost of refrigeration. Many systems, particularly for domestic refrigeration and in air conditioning types, therefore rely solely upon air cooling for

2

condensing the refrigerant. While the use of air for condensing is far less efficient than the ordinary use of water or water combined with air, the cost of the water coolant usually exceeds the saving in cost of power required for compression and no ultimate total of saving in efficiency is achieved.

Our invention contemplates the use for condensing a refrigerant, of an air stream combined with water, but the latter in such small quantities as to be negligible in cost as compared with the saving in power required for compressing the refrigerant, thereby resulting in a large over-all savings in cost of refrigeration.

One of the substantial improvements in the present invention is in the means by which the quantity of cooling water used is reduced by a system which uses a smaller amount of water with greater efficiency and combined with means to re-circulate and reuse the coolant.

For condensing, the coolant water is partly evaporated from cooling surfaces by an air stream and it is the excess unevaporated water which is re-circulated and reused. This would ordinarily result in an increase of the concentration of salts contained in the coolant water, which are deposited in the re-circulation system by the evaporated water, and such concentration would result in eventual plugging of the orifices and parts by concentrated salt. Our invention therefore provides means to drain off a portion of the re-circulated water so as to maintain the salt concentration at a desirable working level. Consequently, means are also provided to replenish the coolant which is lost by evaporation and draining. By reason of the advantageous features of the invention, as will be described, low pressures and large orifices are used for circulating and draining the coolant water, thereby also substantially eliminating the likelihood of plugging and also materially reducing cost not only of the parts of the condenser system but also of the cost of circulating the small amounts of water consumed.

Further advantages will be apparent from the following description taken in connection with the drawings in which:

Fig. 1 is a side elevation in section of the condenser apparatus of the invention;

Fig. 2 is a top plan view with the cover removed;

Fig. 3 is a schematic flow diagram showing the condenser of the invention in combination with the other components comprising the refrigeration system of increased efficiency produced by the invention;

Fig. 4 is a front view of the nozzle; and

Fig. 5 is a section of the nozzle shown in Fig. 4.

In the drawings, Figs. 1 to 3 show a generally box-like container 10 having large round openings 11 and 12 in its ends, thereby forming an air duct having a water-tight bottom providing a sump 13 containing water or other coolant approximately at the level indicated at 14.

In the opening 11 is attached the structure of a fan 15, arranged with a driving motor 16 and a surrounding duct structure 17 so as to create a moving air stream which enters an opening 18 in the duct 17 and flows from left to right through the container 10 and out of the opening 12, and which air stream, due to the rotation of the fan 15, has a vigorous whirling action immediately downstream of the fan 15.

A series of pipes 20, having manifolds or headers 21 and 22 at their ends, form conduit means in the air stream below the fan 15 for cooling and condensing the refrigerant.

erant which may be conducted into the conduit means by an inlet pipe 23 and away from the conduit means by an outlet pipe 24. Surrounding the conduit pipes 20 and in thermal contact therewith, is an arrangement of cooling fins 30 in close proximity to each other with air spaces between through which the air stream of the fan may flow, thereby greatly increasing the cooling surface of the conduit pipes 20.

Located approximately axially of the fan 15, and between the fan and the conduit means 20, is a low pressure nozzle 35 having an aperture 36, preferably of the order of $\frac{1}{8}$ inch in diameter or larger, and of the type illustrated in detail in Figs. 4-5, which delivers a water stream in the form of a wide cone, as illustrated at 38 in Fig. 1, when water is pumped through it from a hose 40 at a pressure of approximately two pounds per square inch. The cooling water is delivered through the hose 40 and the nozzle 35 by a low pressure electrically driven sump pump 45 which is located to draw water 14 from the bottom 13 of the container directly under the nozzle so as to have the shortest possible hose line 40.

Without the aid of the fan 15 the conical stream of water 38 produced by the nozzle 35 plays only on the periphery or surrounding edge areas of the conduit pipes 20 and associated arrangement of fins 30, and a large portion of the central area of the fin arrangement remains dry because no water is projected into the interior of the conical stream of water 38. However, when the fan 15 is in operation, the whirling action of the air stream immediately downstream of the fan agitates the conical stream of water 38 and throws off droplets of water 39 continuously toward the center of the cone and toward the fins 30 in such a manner that the entire effective surfaces of the fins are continually being wet by droplets of water projected upon them by the combined action of the nozzle and the whirling action of the air stream created by the fan.

There is a point of optimum action of the fan on the water stream relative to which the nozzle 35 should be adjusted and spaced with respect to the fan 15, and also a point where the conduit means may be spaced with respect to the nozzle 35 for optimum wetting effect on the fins by the combined action of the fan and the nozzle, both of which can be determined by adjustment of the parts so that maximum wetting and evaporation effect is produced on the fins 30.

As explained in the said co-pending application, the fins 30 are preferably inclined out of the horizontal from approximately 5° to 15° in order to inhibit by gravitational force the flow of water across their surfaces produced by the air stream. With a corresponding adjustment of air stream velocity and angle of inclination of the fins, the coolant water is caused to linger on the fin surfaces in an agitated condition, thereby greatly enhancing the evaporation of the coolant and consequently increasing substantially the cooling and condensing effect on the compressed refrigerant flowing through the conduits 20.

The critical relative locations of the fan 15, the nozzle 35 and the conduit means 20, as described herein, enable us to use the large aperture low-pressure type nozzle 35 and low-pressure type pump 45 in place of a fine spray type of nozzle which would otherwise be necessary to wet the entire area of the fin, and which requires a high pressure pump to produce such a spray. The advantages are that the low pressure system herein uses less water, the low pressure pump is far cheaper to purchase and operate, and what is more important, the large aperture of the low pressure nozzle is unlikely to clog due to whatever sediment may creep into the system, whereas the multiple fine apertures of the high pressure fine spray type nozzle clog more readily and may render the nozzle inoperable after a period of use.

A baffle 55 is provided in the form of a fixed highly porous pad to catch the droplets of water driven off

the fin surfaces by the air stream and to return them to the sump, while at the same time allowing the flow of the air stream therethrough and out of the opening 12.

Means are provided to drain off a portion of the water 5 coolant falling from the fins, in order to keep the salt concentration from building up to an undesirable level due to evaporation, in the form of a tray 60 having a drain 62 in the bottom thereof and the edges 64 of which protrude slightly above the water level 14. By this arrangement most of the water flowing off the fins is returned to the sump for re-circulation but a desired proportion falling into the tray 60 is removed.

Means for replenishing the water supply as necessary is provided in the form of a water inlet 70, automatically 15 controlled by a valve 72 operated by a float 73 so as to maintain the water level 14 at the desired height. The tray 60 also acts as an overflow in the event the float valve sticks, thus preventing flooding.

Figure 3 shows the condenser unit 10 connected to receive compressed refrigerant gas through the line 23 and to discharge condensed liquid refrigerant through the line 24 in a closed refrigeration system, including also an evaporator 80 and a compressor 82. The liquid refrigerant is conducted to the evaporator 80 through the line 24 where, upon evaporating it exerts a cooling effect by absorbing the heat of evaporation, whereupon it passes through a line 84 to the compressor 82 where it is compressed and returned through the line 23 to the condenser 10.

Any of the well known refrigerants, for instance the "freon" gases, may be used in the system. Whereas, it has ordinarily previously required a motor of one rated horsepower to operate the compressor 82 to produce one ton of refrigeration per day in a refrigeration system of this general type, the power requirement for the compressor 82 has now been substantially reduced as a result of this invention, by reason of the fact that while the evaporation temperature in the evaporator 80 for any given refrigerant remains unchanged, the increased efficiency of the condenser 10 of the invention substantially reduces the temperature of condensation of the refrigerant and thereby reduces the power required to compress it.

We claim:

1. In a heat exchanger of the character described, conduit means in thermal contact with fins, said fins being inclined from the horizontal about five to fifteen degrees, a generally horizontally extending duct providing a passage for a stream of air and in which said conduit means and said fins are positioned with the upper edges of said fins disposed downstream relative to the lower edges, means upstream of said conduit means for supplying liquid to the fins in an amount sufficient to continuously maintain substantially the entire surfaces thereof covered with water, a blower positioned upstream of said liquid supplying means to move the air through said duct at a velocity sufficient to substantially completely overcome the gravitational downward flow of liquid on the surfaces of said fins.

2. In a heat exchanger of the character described, conduit means in thermal contact with fins, said fins being inclined from the horizontal, a generally horizontally extending duct providing a passage for a stream of air and in which said conduit means and said fins are positioned with the upper edges of said fins disposed downstream relative to the lower edges, means upstream of said conduit means for supplying liquid to the fins in an amount sufficient to continuously maintain substantially the entire surfaces thereof covered with liquid, and a blower positioned upstream of said liquid supplying means operative to disperse and distribute the liquid from said liquid supplying means over the entire surfaces of said fins and to move the air through said duct at a velocity sufficient to substantially overcome the gravitational flow of liquid

on said fin surfaces and provide a run-off of liquid over the upper and lower edges of the fins.

3. The method of cooling a fluid in a conduit comprising passing said fluid in the conduit in thermal contact with a fin inclined from the horizontal, supplying evaporative liquid upon said fin from adjacent the lower edge thereof and in an amount to substantially completely cover the same, and passing a stream of gas from upstream of the liquid supply so as to disperse and distribute the liquid over the surface of the fin and at a velocity sufficient to substantially completely overcome the free gravitational flow of liquid on the fin and cause a small portion of the liquid to run off from both the upper and lower edges of the fin.
